UNITED STATES PATENT OFFICE

150,260

DESIGN FOR A FOUNTAIN PEN OR SIMILAR ARTICLE

Peter Schladermundt, Bronxville, and Olive Emslie, New York, N. Y., assignors to Stratford Pen Corporation, New York, N. Y., a corporation of New York

Application November 19, 1946, Serial No. 134,900

Term of patent 14 years

(Cl. D74—17)

To all whom it may concern:

Be it known that we, Peter Schladermundt and Olive Emslie, both citizens of the United States, residing in Bronxville, county of Westchester, and State of New York, and New York, county and State of New York, respectively, have invented a new, original, and ornamental Design for a Fountain Pen or Similar Article, of which the following is a specification, reference being had to the accompanying drawing, forming a part thereof, wherein:

Fig. 1 is a side elevational view of a fountain pen, and

Fig. 2 is an elevational view of the barrel portion with the cap removed, showing the essential features of our new design in full lines. The fountain pen is characterized by the relationship between the lower end of the cap and the barrel in which the cap is provided with a bevelled end which engages the central portion of a bevelled collar formed on the barrel.

We claim:

The ornamental design for a fountain pen or similar article, substantially as shown and described.

PETER SCHLADERMUNDT.
OLIVE EMSLIE.
